UNITED STATES PATENT OFFICE.

HENRY M. COSEY, OF FLINT, MICHIGAN.

SAFETY ATTACHMENT FOR AEROPLANES.

Application filed July 27, 1925. Serial No. 46,243.

My invention relates to a new and useful improvement in a safety attachment for aeroplanes.

The present invention has as its object the provision of a safety device which may be mounted on an aeroplane and quickly and easily operated in emergencies for permitting a slow and easy descent of the aeroplane to the earth from an elevated position.

Another object of the invention is the provision of a small umbrella which may be easily and quickly opened by the operator, and, when opened, will, on account of the air currents caught thereby, raise a large parachute out of a housing to serve as a retarding agent in preventing too rapid descent of the aeroplane.

Other objects reside in the novel structure and arrangement of the various parts.

The invention will be best understood by reference to the drawings which form a part of this specification, and in which—

Fig. 1 is a side elevational view of the invention, shown applied to an aeroplane shown in fragment.

Fig. 2 is a sectional view taken substantially on line 2—2 of Fig. 1;

Fig. 3 is a side elevational view of the invention in operative position,

Fig. 4 is a side elevational view showing parts broken away and parts in section of the umbrella used with the invention.

As shown in the drawings, the invention is adapted for use with an aeroplane having a body 7 and any desirable landing gearing 8. Mounted on the body 7 is a superstructure 9. Mounted on this superstructure 9 is a housing or receptacle 10, in which is adapted to be positioned a parachute 11, of sufficient size to permit the gradual falling of the aeroplane with which used. The guy ropes 12 which are attached to the parachute 11 are securely fastened at their ends to the upper portion of the housing 10. Secured to the parachute 11 adjacent its center and projecting therethrough is an umbrella handle 13. In the form shown in the drawings, the handle 13 is formed tubular to provide the chamber 14, in which is slidably positioned a plug 15 to which the ends of the umbrella braces 16 are attached. Mounted on the plug is a catch 17, which co-operates with the latch member 18 for normally retaining the umbrella 20 in closed position. When the umbrella is in closed position, the spring 21 is under tension so that when the

rod 19, which extends downwardly into a position to be easily accessible to the driver of the aeroplane, is pulled downwardly the latch 18 will rock to disengage the catch 17, thus permitting the spring 21 to open the umbrella slightly. The air currents rushing into the umbrella will then serve to open it to its fullest extent. If desired, the spring 21 may be dispensed with, as the air currents rushing into the umbrella are believed sufficient to open the umbrella under ordinary conditions. As the umbrella is opened to receive the air currents in large measure, sufficient resistance is afforded for raising the parachute 11 out of the housing 10 so that the air will have an opportunity to then distend the parachute and permit it to function and retard too rapid descent of the aeroplane.

While I am familiar with different devices in which a parachute is used to retard the descent of an aeroplane. I believe that the employment of an umbrella for the purpose of raising the parachute to operative position is novel, and it is this which forms an important feature of the present invention. The position of mounting the receptacle or housing 10 is also important, inasmuch as the strain to which the aeroplane is subjected when its descent is retarded will be on the fuselage and wings or superstructure 9, which is the most acceptable place for delivering this strain on account of its rigid and durable structure.

While I have illustrated and described the preferred form of construction, I do not wish to limit myself to the precise details of structure shown in the drawings, but desire to avail myself of such variations and modifications as come within the scope of the appended claim.

Having thus described my invention, what I claim is new and desire to secure by Letters Patent is:

A safety device for aeroplanes adapted for use with an aeroplane having a superstructure mounted thereon, comprising a receptacle mounted on the upper surface of said superstructure; a parachute normally folded in said receptacle, the ropes of said parachute being attached to said receptacle adjacent the upper edge thereof; an umbrella mounted on said parachute and having a handle projected through said receptacle and said superstructure, said handle being hollow for a portion of its distance; a

spring mounted in said hollow portion and under tension when said umbrella is closed; means for retaining said spring under tension and said umbrella in closed position, 5 said means being releasable at will for permitting the opening of said umbrella in response to said spring, said umbrella being

adapted when open for engaging air currents for raising said parachute out of said receptacle for permitting the functioning of 10 same.

In testimony whereof, I have signed the foregoing specification.

HENRY M. COSEY.
